SPOOL CONSTRUCTION

George G. Tucker, Jr., Berwyn, and Frederick A. Rappleyea, Oak Park, Ill., assignors to Hubbard Spool Company, Chicago, Ill., a corporation of Illinois

Application December 15, 1949, Serial No. 133,148

3 Claims. (Cl. 242—123)

1

The present invention relates to a spool construction, and in particular to a spool construction having a reinforced head structure capable of sustaining axial thrusts occurring when wire is being wound on the spool.

When wire, ribbon, thread, or the like, is wound upon a spool at the high rate of speed normally used in such winding operations, a substantial axial thrust is imparted to the head of the spool which, in many instances, will cause the head to buckle or become otherwise distorted. This distortion creates an unequal distribution of mass in the rapidly rotating spool assembly, thus interfering with the rotation of the spool on its true geometric axis.

To overcome this difficulty, it is necessary to provide suitable reinforcement for the head members without materially increasing the weight thereof, since it is desirable for shipping and operating purposes to keep the weight of the spool as low as possible.

With the foregoing in mind, an object of the present invention is to provide a spool assembly having a reinforcement head portion capable of sustaining substantial axial thrusts without buckling or deformation.

Another object of the present invention is to provide a spool assembly wherein the head members are locked together so that axial thrust on one head member will be resisted by both of the head structures.

Still another object of the invention is to provide a spool assembly having a reinforced core.

A further object of the present invention is to provide a light-weight spool assembly which may be conveniently fabricated from light-weight metal stampings.

Other and further objects and features of the present invention will be apparent to those skilled in the art from the following description of the attached sheet of drawings, in which:

Figure 1 is a vertical view of a spool produced according to the present invention, with a portion thereof broken away and in section to illustrate the core and head structures; and

Figure 2 is a sectional view taken along the line II—II of Figure 1.

As shown on the drawings:

The spool assembly of the present invention includes a tubular hub member 10 preferably formed from a seamless, extruded piece of metal tubing, such as aluminum. Disposed concentrically with the axis of the hub 10 are a pair of concentric tubular inserts forming the core of the spool structure comprising an inner insert 11 and an outer tubular insert 12.

2

The head assembly of the spool shown in the drawing consists of an annular head member 13 of a suitable metal having its inner peripheral edge rolled to provide an inwardly extending annular flange portion 14 and an adjacent annular bead 15. The flange portion 14 is joined, preferably by brazing, to the outer wall of the outer tubular insert 12.

The head member 13 is also provided with a plurality of integral, inwardly extending curved tab portions 16 struck out from the metal of the head member. The tabs 16 are equally spaced radially from the center of the head member 13. The tabs 16 serve not only to strengthen the head assembly but also serve to center the head and hub assemblies about a common axis. Each of the tabs 16 is rigidly secured to the interior of the hub 10 as by means of brazing or the like.

To rigidly secure the concentric tubular inserts 11 and 12 to the head member, as well as for reinforcing the head structure, there is provided a reinforcing member consisting of an end plate or washer 17. This end plate 17 is of annular configuration and has an inwardly turned rim 18 at the inner peripheral edge thereof snugly received in the space between the inserts 11 and 12. The outer edge of the inner tubular member 11 is peened over the flange 18, as shown at 11a, to aid in securing the flange 18 against outward displacement from between the tubular members 11 and 12. In the completed assembly the bead 15 formed in the head member 13 is in contact with the surface of the end plate 17 and is secured thereto as by means of brazing.

The outer peripheral edge 19 of the reinforcing member 17 is rolled and nestled within the rolled rim 20 of the head member 13 to unite the peripheral edges of the two members.

A keyway 21 is formed in the end plate 17 to receive a drive pin for transmitting torque to the spool assembly.

In assembling the spool of the present invention, a sub-assembly consisting of the hub 10, head member 13, and outer tubular insert 12 are first assembled. The areas of the hub 10 which are to be fastened to the tabs 16 are pre-coated with a brazing compound, as in the flange portion 14 of the head member 13. Upon assembly of these three components, the joints are brazed by the addition of a suitable flux and the application of heat. Brazing compounds of this nature are normally corrosive, so after brazing has been accomplished it is desirable that access to the joints be had so that excess brazing compound may be removed. The apertures 22 resulting from the offsetting of tabs 16 from the head member

13 provide convenient points of access through which a brush may be inserted to clean the brazed joints. The end plate 17 and the inner insert 11 may then be assembled within the previously mentioned sub-assembly and secured by peening over the edge 11a of the insert 11 and rolling the edge 20 of the head member 13 over the outer edge of the end plate 17.

While only one head structure has been illustrated for purposes of convenience, it will be understood that the structure of the opposite head is identical with the structure of the head assembly shown. In this manner, when a thrust load in an axial direction due to the pressure of the medium being wound is exerted on one of the head members, the force will be resisted by both head assemblies. In addition, a force applied against one of the head assemblies tending to force it off the hub will, due to the interaction of the two head assemblies, tend to force the opposite head assembly against the adjacent end of the hub.

It will be appreciated by those skilled in the art that in the present invention we have provided a spool assembly having both reinforced head and core portions capable of sustaining a high degree of stress. The spools of the present invention may be conveniently fabricated from relatively inexpensive tubing and stamped sheet metal sections so that the weight of the completed spool is conveniently low and consequently possesses a low degree of inertia.

It will be understood that modifications and variations may be effected without departing from the scope of the novel concepts of the present invention.

We claim as our invention:

1. A spool comprising a tubular hub, a pair of concentric tubular inserts aligned axially within said hub, an annular head member secured at its inner peripheral edge to the outer one of said inserts and having a plurality of integral tabs extending therefrom joined to the

interior of said hub, and an annular reinforcing member having its inner edge disposed in snug fitting relation between said inserts, and having its outer peripheral edge joined to the peripheral edge of said head member.

2. A spool comprising a tubular hub, a pair of concentric tubular inserts aligned axially within said hub, an annular head member having a rolled inner edge forming a flange portion and a bead portion, said flange portion being secured to the outer of said tubular inserts, a plurality of inwardly extending tabs formed in said head member and secured to said hub within the interior thereof, and an annular reinforcing member having an annular flange thereof in snug engagement between said tubular inserts, having a surface thereof secured to said bead portion, and having its outer peripheral edge secured to the peripheral edge of said head member.

3. A spool comprising a tubular hub, a pair of concentric tubular inserts aligned axially within said hub, an annular head member having its inner peripheral edge secured to the outer of said inserts, a plurality of tabs integral with said head member and equally spaced from the center of the head member secured to the inner surface of said hub, and an annular reinforcing member having an inwardly turned flange snugly held between said tubular inserts and having its outer peripheral edge secured to the peripheral edge of said head member.
